ABSTRACT

A system comprises a sewing machine, a clutch-brake motor for driving said sewing machine at high speed, a foot treadle, and an electric circuit for controlling the machine operation. The machine is operated by the circuit in such a manner that non-raveling seam is applied at the end of lock stitch seam at high speed when the foot treadle is operated.

CONTROL SYSTEM FOR A SEWING MACHINE

The present invention relates to a control system for a sewing machine including non-ravel seaming device which can quickly and automatically make non-raveling seam at the start and terminal ends of sewing operation.

The conventional non-ravel seaming process at the start of sewing consists in light depressing a foot treadle connected to a clutch and brake motor to slow down the sewing speed of the sewing machine and under this condition continuing sewing up to a desired point, manually actuating a work feed reversing mechanism to sew the work fabric over a slight length under such condition, releasing the work feeding reversing mechanism to bring the work feed back to the original direction and upon completion of the non-ravel seaming properly depressing the foot treadle to perform the desired normal sewing. Also the non-ravel seaming process at the end of sewing consisted in stopping the depression of a treadle connected to the clutch and brake motor of a sewing machine as sewing is drawn near its termination so as to slow down the sewing speed, thereby reliably carrying out sewing up to the desired point, manually operating a work feed reversing means to sew only a small portion of the work at reverse feed, releasing said work feed reversing means to bring the work feed back to its normal direction and perform sewing again at normal feed.

The aforesaid conventional non-ravel seaming process had the drawbacks that there was not only required manual operation each time non-ravel seaming was conducted until one cycle of sewing was completed, but also operating efficiency was reduced because sewing speed has to be slowed down. Moreover, since the amount of non-ravel seaming was determined by the length of time the treadle was depressed, as well as by the period and time a work feed reversing mechanism is operated there resulted irregular or in some cases unduly insufficient non-ravel seaming. Also lowering in commercial value of the finished articles resulted.

The primary object of the present invention is to provide a control system for a sewing machine, capable of performing an automatic non-ravel seaming, at the start and end of sewing, by the operation of a foot treadle. The other object of the present invention is to provide a control system for a sewing machine capable of performing an automatic non-ravel seaming at high speeds and without involving any slowdown of sewing speeds, and capable of enhancing the efficiency of sewing operation. The further object of the present invention is to provide a control system for a sewing machine, capable of performing an automatic non-ravel seaming of predetermined length at the start and end of sewing to obtain a uniform seam of non-ravel sewing without involving the lowering in commercial value of the finished article. Still further object of the present invention is to provide a control system for a sewing machine, capable of stopping the needle in an upper position subsequent to a non-ravel seaming performed in the terminal end of the work fabric after the end of a series of sewing operations, and operating a thread cutting mechanism whereby the efficiency of operation can be more enhanced. Still further object of the present invention is to provide a control system for a sewing machine, capable of attaining the above ob-

jects with a simpler construction and in a form suitable for purposes.

This invention can be more fully understood from the following detailed description given by way of example with reference to the accompanying drawings, in which:

FIG. 1 is a schematic pictorial view of an entire sewing machine according to an embodiment of the present invention which is equipped with a clutch and brake motor;

FIG. 2 schematically presents the drive mechanism of said sewing machine;

FIG. 3 is an elevation, partly broken away, of a clutch and brake motor;

FIG. 4 is a bottom view of the operating mechanism of the clutch and brake motor of FIG. 3;

FIG. 5 is a cross sectional view taken on line 5—5 of FIG. 3;

FIG. 6 is a cross sectional view of an auxiliary motor attached to the clutch and brake motor of FIG. 5;

FIG. 7 is a cross section of the foot treadle of the sewing machine of FIG. 1;

FIG. 8 is a cross sectional view of the ring switch mechanism of the sewing machine of FIG. 1;

FIG. 9 is a cross sectional view of the individual ring switches where the switch mechanism of FIG. 8 is dismembered;

FIG. 10 illustrates the relative positions of the "ON" and "OFF" regions of the respective ring switches;

FIG. 11 is a schematic pictorial view of the work feed mechanism of the sewing machine of FIG. 1;

FIG. 12 indicates an electrical control circuit for driving the sewing machine of FIG. 1;

FIG. 13 is a time chart for explanatory illustration of the sewing machine operation; and

FIGS. 14A and 14B show a modification of an actuating lever structure of the sewing machine.

Referring to FIGS. 1 and 2, the reference numeral 20 denotes a sewing machine, and 21 is its main shaft, rotatably supported on the frame of said sewing machine 20. The main shaft is fitted with a pulley 22 and ring switch assembly 23 as will be later set forth. 24 is a reciprocable needle supported on the frame and drivingly connected to the main shaft 21 and 25 is a presser foot urged downward by a built-in spring 26. Said foot 25 is coupled with an interlocking mechanism 30 consisting of a lever 27, connection rod 28, and bell crank 29. The interlocking mechanism 30 is connected to the piston rod 32 of a fluid pressure cylinder 31. 33 is an electrical control valve attached to the first fluid pressure cylinder 31 so as to transfer fluid stream. Said electrical control valve 33 is actuated upon energization by a first solenoid 34 to lift the presser foot 25 and keep it at an upper position. 40 is a thread cutting mechanism rockably fitted to the underside of a throat plate, which is connected to the piston rod 36 of a second fluid pressure cylinder 35. 37 is an electrical control valve attached to the second fluid pressure cylinder 35 so as to transfer fluid streams. On both sides of said valve 37 are disposed second and third solenoids 38 and 39 which are alternately energized. Movement of the piston rod 36 upon energization by the second solenoid 38 causes the thread cutting mechanism 40 to rock one way to take hold of upper and lower threads, while movement of the piston rod

36 resulting from energization by the third solenoid 39 causes the thread cutting mechanism 40 to rock the other way so as to cut thread.

A clutch and brake motor as shown in FIGS. 2 to 6 includes a main motor 41 disposed in a bracket 42, which consists of a stator 43 and rotor 44. One end of the rotary shaft 45 of the rotor 44 extends through a bearing 46. To the projecting end of said rotary shaft 45 is fixed by a bolt 48 a flywheel 47 fitted with a friction plate 56. 49 is a hollow bearing cylinder received in an end bracket 50 in coaxial relationship with the rotary shaft 45.

With the periphery of the bearing cylinder 49, FIG 3 is rotatably engaged an annular worm wheel 55 through a bearing 51. 52 is a brake wheel having a friction plate 53 fitted on one side. This brake wheel 52 is connected by bolt 54 to that side of the worm wheel 55 which faces the flywheel 47. 58 is a movable shaft supported to a sleeve 57 journaled in the bearing cylinder 49 so as to slide therethrough in its axial direction. To the inner end of said shaft 58 is connected by a bolt 61 a clutch disk 60 interposed between the friction plates 52 and 56. To the outer end of said shaft 58 is connected a pulley 62 by a bolt 63. 70 is an auxiliary motor, FIG. 6 which consists of a stator 71 and rotor 72. One end of the shaft 77 of the rotor 72 is supported on one end bracket 73 through a bearing 74 and the other end of said shaft 77 projects through a bearing 76 from the other end bracket 75. Outside of the end bracket 75 are provided inner and outer chambers 78 and 79 partitioned by a double cylindrical wall disposed around the rotary shaft 77. To that end of the rotary shaft 77 which projects into the inner chamber 78 is fixed by bolt 82 a connection wheel 81 having a friction engaging member 80 fitted to its side. In the outer chamber 79 is received a clutch coil 83, for example, an annular solenoid. 84 is a clutch side bracket connected to the end bracket 75 and 85 is a worm gear side bracket connected to said clutch side bracket 84 by a bolt 86. The latter bracket 85 is integrally formed with the end bracket 50 facing the main motor 41. 87 is a worm gear engaging the worm wheel 55. One end of a shaft 88 integrally formed with said worm gear 87 is pivoted to the outer end of the bracket 85. The other end of said shaft 88 is inserted into the clutch side bracket 84 with the intermediate portion supported by a bearing 89. 90 is a coil case received in the clutch side bracket 84 so as to surround the shaft 88. This coil case 90 having a side contact member 93 houses a brake coil 140, and an attractive plate 91 and is connected by a bolt 92 to the clutch side bracket 84. 94 is a clutch disk fitted with a brake member 95 slidable on the shaft 88 in the axial direction thereof. Said clutch disk 94 is interposed between the friction engaging member 80 of the connection wheel 81 and the contact member 93 and is connected to the end of the shaft 88 so as to move in it axial direction. As shown in FIG. 3 100 is a main actuating lever assuming as a whole an L-shape. The two portion divided by the bent point are designated as one arm 101 and the other arm 102 respectively. From the bend of said main actuating lever 100 projects a two-forked pressure contact means 103a comprising a pressure contact member 103. The end of said one arm 101 is rotatably supported by a shaft pin 105 on a support member 104 projecting from the end bracket 50. 106 is

a spring support rod freely penetrating said one arm 101, one end of said rod 106 being fixed to the end bracket 50. Into the end bore of said one arm 101 penetrated by the spring support rod 107 is idly inserted a coil spring so as to press said one arm 101. Said spring 107 is kept in a compressed state by screwing a wing nut 108 onto the end of the spring support rod 106. 109 is a limit stop arm screwed through said arm 101. The end of said stopper 109 normally contacts the end bracket 50 and is prevented from being loosened by a nut 110. 111 is an intermediate lever whose cross section substantially assumes a horizontally disposed U-shape. Said lever 111 is pivotally connected at a certain point along its length to the end of said other arm 102 by a shaft pin 112. Substantially to the right side and adjacent the end of said lever 111 as shown in FIG. 4 is fitted by a screw 114 a thread cutting switch S₃ comprising an actuating strip 113. 115 is a coil spring, 20 part of which is received in a recess 116 formed in said other arm 102. The upper end of said coil spring 115 contacts the underside of the end of the intermediate lever 111. Said coil spring 115 is guided by a bolt 117 extending freely through the end of the intermediate lever 111, said bolt 117 being embedded in said other arm 102. 118 is a stopper penetrating throughout the intermediate lever 111. The lower end of the stopper 118 contacts the end of said other arm 102. 119 is an actuating plate which is fixed by screw 120 to the end of said other arm 102 in such a manner as to face the actuating strip 113 of the thread cutting switch S₃. Into that part of said actuating plate 119 which faces the actuating strip 113 is inserted a press screw 121. 122 is an auxiliary actuating lever consisting of a pair of plate members surrounding said one arm 101 of the main actuating lever 100, the intermediate part of said lever 122 being rotatably pivoted to the shaft pin 105. The upper end of said lever 122 is connected through an opening 123 formed in the underside of the bearing cylinder 49 to a shaft pin 124 engaging the annular groove 59 of the sleeve 57. To the lower end of the auxiliary actuating lever 122, FIG. 4, is horizontally fitted another shaft pin 125. The shaft pin 125 is contacted by 40 the press member 103 of the main actuating lever 100. As shown in FIG. 4 126 is a connection member rotatably connected to the shaft pin 125 and there is interposed a coil spring 128 in a compressed state between one end of said connection member 126 and a spring support 127 substantially assuming a horizontally thrown U-shape which is fixed to the main actuating lever 100. 129, FIG. 3, is a fluid pressure cylinder including a fourth solenoid 129a. When there is introduced high pressure fluid into the fluid pressure cylinder 129 upon energization of the solenoid 129a, the piston rod 130 of which is pushed forward. The fluid pressure cylinder 129 is fitted through a support plate 131 below said other arm 102 of the main actuating lever 100 by a shaft screw 132 in a manner to rotate about it. The end of the piston rod 130 is integrally connected to the other end of the connection member 126. 134 as shown in FIG. 1 is a foot treadle positioned below a sewing machine bed. The treadle 134 is fitted with a connection rod 136 the upper end of which is connected to the end of the intermediate lever 111. Said foot treadle is normally positioned in a rest position and operable in a downward direction by depression

sion of the toe of the operator to actuate the main actuating lever 100, and in any upward direction beyond the rest position by the heel of the operator. Into the lower end of the auxiliary actuating lever 122 is inserted a press screw 142, in FIG. 4, in a manner to penetrate it. The screw 142 is prevented from being loosened by a nut 143. S₁ denotes a start switch fitted to a support 175 mounted on the bracket 50. The start switch S₁ is normally opened with its actuating strip 146 pressed by the press screw 142, and closed when the actuating strip 146 is released.

There will now be described the operation of a clutch and brake motor constructed as above described. Let it be assumed that the main motor 41 and auxiliary motor 70 FIG. 2, are brought into an operable state without any manual operation applied to the main and the auxiliary levers 100 and 122. Since the brake member 52 and clutch disk 60 are separated, the flywheel 47 continues no-load rotation. On the other hand, where, on the side of the auxiliary motor 70, the clutch coil 83 is excited, FIG. 6, the clutch disk 94 frictionally engages the friction engaging member 80 of the connection wheel 81 to cause the worm gear 87 to rotate, and in consequence the worm wheel 55 engaging the worm gear 87 slowly rotates around the bearing cylinder 49. Under such condition, namely, where the foot treadle 134 is not depressed but keeps a neutral position, the clutch disk 60 on the side of the main motor 41 is pressed, as described later, to the friction plate 53 of the worm wheel 55 by the action of the coil spring 107 and 128. Accordingly, the rotation of the worm wheel 55 is transmitted to the pulley 62 through the clutch disk 60 and movable shaft 58. At this time, the pulley 62 is in a slowly rotating state. When, under such condition, the foot treadle 134 is depressed in the downward direction (that is, toward the start side), then the intermediate lever 111 is pulled downward through the connection rod 136, and the other arm 102 of the main actuating lever 100 is depressed by the joint action of the stopper 118 and shaft pin 112 of said intermediate lever 111 to rotate about the shaft pin 105 in the direction indicated by the arrow 137, FIG. 3. As a result, the press contact member 103 presses the shaft pin 125, causing the auxiliary actuating lever 122 to rotate about the shaft pin 105 similarly in the direction indicated by the arrow 137. Accordingly, the sleeve 57 moves through the shaft pin 124 in the direction indicated by the arrow 138, carrying with it the movable shaft 58, so that the clutch disk panel 60 is pressed to the friction plate 56 of the flywheel 47 which is rotating without load and is frictionally coupled with said wheel 47, with the resultant high speed rotation of the pulley 62. In the aforesaid operation, the coil spring 107 supplies the main actuating lever 100 with a force to rotate opposite to the direction indicated by the arrow 137. The other coil spring 128 supplies the auxiliary actuating lever 122 with a force to rotate similarly opposite to the direction of the arrow 137. When the foot treadle 134 is released, the clutch disk 60 is pressed to the side of the worm wheel 55. Where the brake coil 140 of the auxiliary drive is excited while the pulley 62 slowly rotates, the clutch panel 94 is attracted thereby and the brake member 95 of said disk 94 slides to the slide contact member 93 so as to effect braking, with the resultant stop of the pulley 62. The clutch and brake

motor can be controlled by means of the fluid pressure cylinder 129. The electrical control valve of the fluid pressure cylinder 129 is energized to conduct high pressure fluid into the cylinder to cause the piston rod 130 of said cylinder 129 to be pushed forward, to rotate the auxiliary actuating lever 122 in the direction of arrow 137, FIG. 3, when the foot treadle 134 is operated in the upward direction beyond the rest position. When the electrical control valve is deenergized, the high pressure fluid ceases to be supplied, causing the auxiliary actuating lever 122 to be returned by the action of the coil springs 107 and 128. The coil spring 115 serves to energize the intermediate lever 111 for its rotation about the shaft pin 112 in the direction of the arrow 147 and also normally to leave the thread cutting switch S₃ open by causing the press strip 113 to contact the press screw 121.

There will be described a modification of the actuating lever structure with reference to FIGS. 14A and 14B.

FIG. 14A shows normal operating conditions while FIG. 14B a non-raveling seaming operation.

The apparatus includes a main actuating lever 338 associated with the foot treadle, which is swingable around an axle 339. The cutting portion 340 formed at one end of the lever 338 is abruptly stopped by a fixed axle 342 projected from a displacement body 341 through which the axle is loosely inserted. Numeral 343 denotes an auxiliary actuating lever pivoted on the axle 339, one end of the lever 343 being connected to the fixed axle and the other end to a piston rod 345 of pressure cylinder 344 mounted on the actuating lever 338. 346 shows an actuator of the cylinder 344 where there are provided two solenoids 348 and 349 alternatively operating. Numeral 347 denotes a coil spring provided between both levers 338 and 343 in such a manner that it urges both levers to swing them in the opposite directions. Reference P is a pressure Source In the apparatus there is a switch, though not shown in the figures, which starts the machine operation when the foot treadle is operated in the upward direction beyond the rest position.

The foot treadle 134 is provided, as shown in FIG. 7, with a normally closed switch S₂ for lifting the pressure foot which is turned off prior to the operation of the switch S₁ in the initial stage of the depression of the foot treadle 134 in the downward direction and a thread cutting switch S₃ for closing the thread cutting control circuit which is turned on by the operation of the foot treadle 134 in the upward direction beyond the rest position. The switch S₂ is disposed on the underside of an auxiliary treadle 134 a consisting of, for example, a flexible plate which is located at the rear part of the foot treadle. 134. Where the foot treadle is not depressed either way, that is, is left in an inoperable state, the main actuating lever 100 causes the clutch disk 60 to contact the brake wheel 52.

There will now be described the ring switch assembly 23 mounted on the main shaft 21 of the sewing machine which acts as a mechanism for arresting the needle at a prescribed position with reference to FIGS. 8 and 10 where the needle is brought down. The ring switch assembly 23 consists of a common ring 150 fixed on the main shaft 21, a thread cutting position detecting ring 151 wherein a periphery extending through about 300°

is designated as an "OFF" region, a needle upper position detecting ring 152 wherein a periphery of about 60° is defined as an "OFF" region, and a needle lower position detecting ring 153 whose "OFF" region is represented by a periphery of about 17°. The phases of the "ON" and "OFF" regions of the other rings 151, 152 and 153 are so adjusted as to have a relation shown in FIG. 10. The rings 151, 152 and 153 are contacted by brushes 151a, 152a and 153a to constitute a thread cutting position detecting contact S₄, needle upper position detecting contact S₅ and needle lower position detecting contact S₆ respectively.

Referring to the work feed mechanism shown in FIG. 11, the reference numeral 160 denotes a two-forked rod engaged at one end with the work feed cam 161 of the main shaft 21 and at the other end with a horizontal work feed advancing shaft 162. This shaft 162 rocks by the rotation of the work feed cam 161. 163 is a work feed bar provided with a feed dog 164. Said work feed bar 163 is connected at one end to the horizontal work feed advancing shaft 162 so as to rock horizontally, and at the other end to a pendulum 166 mounted on a vertical feed lifting shaft 165 in a manner to rock vertically. When the horizontal feed advancing shaft 162 and vertical feed lifting shaft 165 rock, the feed dog 164 makes four feed motions by a composition of said rockings to perform a work feed action. A feed reversing means involved in the work feed mechanism is operated in the following manner. 167 is a feed adjusting means disposed at the fulcrum of the two-forked rod 160 and provided with a dial 167a for controlling the work feed. To said feed adjusting means 167 is connected the feed reverse arm 170 of a reversing shaft 169 provided with a reversing lever 168. When this reversing lever 168 is pushed down, the feeding direction of said dog 164 is turned from a forward to a backward movement on the bed of a sewing machine. 171 is a fourth fluid pressure cylinder rockable supported by a pin 173 on a support member 172 fitted to the underside of said machine bed. The piston rod 174 of the cylinder 171 is connected to an arm 175 fixed to the reversing shaft 169. To the arm 175 is connected a spring member 176 for urging the reversing shaft 169 in an opposite direction. 177 is an electrical control valve for transferring fluid streams which is attached to the fourth fluid pressure cylinder 171. The electrical control valve 177 is provided with a fifth solenoid 178, which, when energized, feeds fluid streams in a direction of pushing up the piston rod 174. Energization of the solenoid 178 causes the piston rod 174 to be forced upward, the reversing shaft 169 to rotate in an opposite direction and the feed dog 164 to move backward. 179 is a source of compressed fluid, for example, a compressor.

There will now be described with reference to FIG. 12 an electrical control circuit to effect the proper function of the entire sewing machine mechanism. The reference numeral 181 is a transformer, whose primary winding 182 is connected to an A.C. source 183. Both end of the secondary winding 184 of the transformer 181 are connected to two buses or power source lines 183 and 186 through one full wave rectifier 185. Across the power source lines 186 and 187 is a smoothing circuit consisting of a resistor 188 and condenser 189 connected in series. The circuit energized by the voltage impressed across the power source lines

is arranged as follows. Across the power source lines is connected a serial circuit consisting of the start switch S₁, diode 191 and relay 190 energized through the diode 191 by the closure of the switch S₁. Across the cathode of the diode 191 and the first power source line 186 is connected a serial circuit comprising the normally open contact element 190a₁ of the relay 190 and a needle lower position detecting contact element S₆. Thus these serial circuits constitute the self-holding circuit of the relay 190. Parallel with the needle lower position detecting element S₆ is connected a serial circuit consisting of a condenser 192 and diode 193 for preventing inverse discharge, to which there is connected a resistor 194. 195b₁ is the normally closed contact element of the later described thread cutting relay 195, one end of which is connected to the first line 186 and the other end of which is connected to a control line 197 through the normally open side of the switching contact element 196c₁ of the later described relay 196. Across the control line 197 and the anode of the diode 191 are connected a three-terminal thyristor 198 and start non-ravel seaming switch S₈. Accordingly, the control line 197 is supplied with power by the first power source line through the start switch S₁, and element S₈ and 198. Between the control line 197 and second line 187 are connected a serial circuit consisting of the relay 196 and three-terminal thyristor 199 and a simulation load 200. 201 is another control line connected to said control line 197 through the normally closed side of the switching contact element 196c₁. Between the control line 201 and second line 187 is disposed a timer device 202 energized by the voltage prevailing therebetween so as to set the time of reversion.

The timer device 202 is intended to actuate the work feed reversion mechanism in a prescribed length of time after the start of a sewing machine. Said timer device 202 is arranged as follows. Between the control line 201 and second line 187 is connected a serial circuit consisting of a resistor 203 and constant voltage diode 204. Parallel with said diode 204 is connected a time constant circuit consisting of a resistor 205, variable resistor 206 and condenser 207 connected in series. Further parallel with the diode 204 is connected a unijunction transistor 209, through resistors 210 and 211 connected to the base regions of the transistor. The emitter of the transistor 209 is connected to the junction between the variable resistor 206 and condenser 207. Accordingly, the transistor 209 is energized by a voltage prevailing across both terminals of the constant voltage diode 204. Between the control line 201 and second line 187 are connected in series a relay 213 and three-terminal thyristor 212. The gate of the thyristor 212 is connected through a diode 214 to the juncture between the transistor 209 and resistor 211. Thus the diode 214 is energized by a voltage prevailing across the terminal of the resistor 211.

With the timer device 202 of the aforementioned arrangement, when the control line 201 is impressed with a voltage, the condenser 207 begins to be charged. When the terminal voltage of the condenser 207 attains a prescribed value after a preset time (as determined by the resistivities of the resistors 203, 205 and 206 constituting a time constant circuit), then the transistor 209 is conducted and the thyristor 212 is also con-

ducted by being supplied with gate signals through the diode 214 to actuate the relay 213.

The reference numeral 215 indicated in the circuit denotes a reversion timer device concurrently acting as the first and second timer devices which set the period during which the work feed and reversion mechanisms are separated when non-ravel seaming is performed at the start and end of sewing.

To this reversion timer device, there is connected between the buses 186 and 187 a serial circuit consisting of the fifth solenoid 178 and transistor 226. Between the control line 201 and second line 187 are connected the normally open contact element 213a₁ of the relay 213, a diode 217 and a resistor 252. To the cathode of the diode 217 is connected further control line 216, to which there is connected one end of still further control line 218 through a resistor 219. To the other end of the control line 218 are connected in turn a resistor 220, two variable resistors 221 and 222 alternately actuated by the switching contact element 213c₁ of the relay 213 and a condenser 223 connected to said resistors 221 and 222, thus constituting a time constant circuit. The reference numeral 224 is a unijunction transistor, one base of which is connected to the control line 218 through a resistor 225, the other base of which is connected to the second line 187 through the primary winding PT₁₁ of a first pulse transformer PT₁, and the emitter of which is connected to the juncture between the resistors 221 and 222 and the condenser 223. As the result, the emitter is energized by a voltage impressed across the condenser 223, thereby causing the transistor 224 to be conducted in a prescribed length of time. Between the cathode of the diode 217 and second line 187 is connected a serial circuit consisting of a resistor 228 and three-terminal thyristor 227. The anode of the thyristor 227 is connected to the base of the transistor 226. The reference numeral 231 shown in the figure denotes a constant voltage diode interposed between the control line 218 and second line 187. 253 and S₁₀ respectively represent a diode connected between the lines 186 and 187 and a manual switch for manually operating the work feed and reversion mechanisms. Further between the power source lines 186 and 187 is connected a serial circuit consisting of a needle upper position detecting contact element V₅, normally open thread cutting switch 3, the normally closed contact element 229b₁ and relay 230 associated with the switching contact element 190c₁ of the relay 190. The reference numeral 232 denotes further control line, which is connected through the terminal non-ravel seaming switch S₉ to the juncture between the thread cutting switch S₃ and switching contact element 190c₁. To the thread cutting switch S₃ is connected in parallel the normally open contact element 233a₁ of the relay 223. Between the control line 232 and second line 187 are respectively connected relays 233 and 229 energized by a voltage impressed therebetween. Two buses of a transistor 234 are directly connected to said relay 229 and the base 187. To the control line 232 is connected further control line 237 through a three-terminal thyristor 235 and resistor 236. Between the control line 237 and second line 187 is provided a timer device 238 of substantially the same arrangement as the aforementioned timer device 202, which also sets the point of time at which

sewing is brought to an end. Referring to said timer device 238, the reference numerals 239 to 242 indicate resistors, 243a condenser, 204 a variable resistor, 244 a unijunction transistor, 245 a diode, and 246 a three-terminal thyristor serially connected to the resistor 242. The anode of the thyristor 246 is connected through a resistor 247 to the base of the transistor 234.

The movable strip of the switching contact element 233c₁ of the relay 233 is connected to the first line 186, and the fixed contact strip on the normally open side of the switching contact element 233c₁ is connected to the normally open side of the switching contact element 190c₁. The brake coil 140 which is connected at one end to the first line 186 is connected at the other end to the second line 187 through the normally closed side of the switching contact element 190c₂ of the relay 190 and also through the normally closed side of the switching contact element 230c₁ of the relay 230. The clutch coil 83 which is connected at one end to the first line 186 is connected at the other end to the second line 187 through the normally open side of the switching contact element 230c₁. The fixed contact element on the normally open side of the switching contact element 233c₁ is connected to the fixed contact element on the normally open side of the switching contact element 190c₂. To the normally closed side of the switching contact element 233c₁ are connected the first solenoid 34 and normally closed switch S₂ in turn. The normally closed switch S₂ for lifting the pressure foot is connected to the fixed contact element on the normally closed side of the switching contact element 190c₂. The reference numeral 229a₁ is the normally open contact element of the relay 229. Between the first and second lines 186 and 187 is connected a serial circuit consisting of said normally open contact element 229a₁ and the fourth solenoid 129a serially connected thereto. Further between the power source lines 186 and 187 are connected a serial circuit consisting of the thread cutting position detecting element S₄, thread cutting relay 195 and the normally open contact element 230a₁ of the relay 230 and another serial circuit consisting of the second solenoid 38, and the normally open side of the switching contact element 195a₁ of the relay 195. The normally closed side of the contact element 195a₁ is connected to the power source line 186 through the third solenoid 39.

The reference numeral 248 shown in the figure is a three-terminal thyristor, the anode of which is connected to the first line 186 through the normally open contact element 229a₂ of the relay 229 and the cathode of which is connected to the control line 216. The reference character PT₂₁ denotes the primary winding of a second pulse transformer PT₂. Said winding PT₂₁ is connected at one end to the second line 187 and at the other end is connected to a parallel circuit consisting of a resistor 249 and condenser 250 and to the first line through the thread cutting position detecting element S₄. The two secondary windings designated as PT₁₂ of the first pulse transformer PT₁ are connected between the cathodes and gates of the two thyristors 199 and 227. The three secondary windings indicated as PT₂₂ of the second pulse transformer PT₂ are respectively connected between the cathodes and gates of the three thyristors 198, 235 and 248. 251 denotes the gate bias resistors of the thyristors 198, 199, 212, 235, 246, 227

and 248;252 is a resistor for assuring power supply to conduct each of the thyristors 235 and 248; and 253 is a diode for controlling spike voltage.

There will now be described with reference to the time chart of FIG. 13 the non-ravel seaming operating of a sewing machine constructed as described above. The lines of the figure present the operating condition.

(I) Start (Refer to FIG. 13)

When there is thrown the power source switch of the main and auxillary motors (not shown), the motor 40 is brought into an operable state and there is supplied an alternating current from the A.C. source 183 through the transformer 181 to the wave rectifier 185, where the alternating current is subjected to full wave rectification, so that there is impressed a D.C. voltage across the power source lines 186 and 187. When the aforesaid power source switch is closed, there are also manually thrown the start and end non-ravel seaming switches S_8 and S_9 . Under such condition, the first solenoid 34 is energized through the switch S_2 and the normally closed side of the three switching contact elements 233c₁, 190c₂ and 230. The piston rod 32 of the first fluid pressure cylinder 31 is urged in a direction of pushing the connection rod 28 to lift the pressure foot 25 against the built-in spring 26. On the other hand, the fourth solenoid 129a for the auxiliary actuating lever 122 is not actuated, so that said control lever 122 is kept parallel with the main actuating lever 100 through spring by the piston rod 85 of the fluid pressure cylinder 84.

(II) Sewing and start non-ravel seaming operation
(Refer to T₁ to T₄ in FIG. 13)

When the foot treadle 134 is depressed in a downward direction from the rest position to drive a sewing machine, the switch S_2 is opened by the auxillary treadle 134a to deenergize the first solenoid 34, so that the pressure foot 25 is brought down by the spring 26 to keep the work on the machine bed. At the time of T₂ of FIG. 13 the start switch S_1 is closed and the main actuating lever 100 rotates about the shaft 105 in the direction of the arrow 137, causing the auxiliary actuating lever 122 to move the sleeve 57 with the movable shaft 58, and the clutch disk 60 to be pressed to the flywheel 47 in high speed rotation. Thus the main shaft 21 is turned quickly to start the sewing operation. When the sewing machine makes such a high speed run, the ring switch assembly 23 is also brought into an operable state. The thread cutting position detecting contact element S_4 , needle upper position detecting contact element S_5 and needle lower position detecting contact element S_6 involved in the ring switch assembly 23 are operated with a period shown in FIG. 13. In the meantime the primary winding PT₂₁ of the second pulse transformer PT₂ is energized by pulses from the thread cutting position detecting contact element S_4 to generate pulses synchronizing therewith in the secondary winding of the transformer PT₂. On the other hand, the closure of the start switch S_1 causes the relay 190 to be actuated and brought into a self-holding position by the current flowing through the normally open contact element 190a₁ and needle lower position detecting contact element S_6 . In this case, the needle lower position detecting contact element S_6 is turned

off each time the brush 153a passes through the "OFF" region of the needle lower position detecting ring 153. Since, however, the main shaft 21 of the sewing machine is rotated at high speed, the relay 190 is kept in a self-holding position by the current discharged from the condenser 192 during the "OFF" period of the needle lower position detecting contact element S_6 . At this time the switching contact elements 190c₁ and 190c₂ of the relay 190 are charged over, causing the clutch coil 83 to be excited by the latter contact element 190c₂. Since the clutch disk 94 is attracted to said connection wheel 80 the clutch disk 67 is driven through the worm 87 and worm gear 55 into a slow no-load operation. When the sewing operation is reliably started, namely, when the thread cutting contact element S_4 starts operation to cause pulses to be generated in the secondary winding PT₂₂ of the second pulse transformer PT₂, then the thyristor 198 is conducted to supply voltage to the control lines 197 and 201 and energize the timer device 202. After a prescribed length of time (at the time T₂ in FIG. 13), the transistor 209 is conducted by the charged current of the condenser 207, with the resultant conduction of the thyristor 212, so as to actuate the relay 213. Accordingly, the variable resistor 222 is selectively operated by the switching contact element 213c₁ and the reversion timer device 215 is energized by the closure of the normally open contact element 213a₁. As the result, the transistor 226 is conducted by the current passing through the resistor 228 to excite the fifth solenoid 178. The piston rod 174 of the fourth fluid pressure cylinder 171 is pushed upward and in consequence the feed dog 164 is changed to make a backward movement opposite to that which it has performed up to this point, so as to reverse the work feed and start non-ravel seaming quickly. This non-ravel seaming is continued until the period preset by the reversion timer device 215 is brought to an end. When the lapse of said period is determined by the time constant defined by the variable resistor 222 and condenser 223, the transistor 224 is conducted to energize the primary winding PT₁₁ of the first pulse transformer PT₁ and generate pulses in the secondary winding PT₁₂ thereof (at the time T₄ in FIG. 13). As the result, the thyristor 227 is conducted and the transistor 226 is shut off to deenergize the fifth solenoid 178, so that the reversing shaft 169 is made to rotate in the normal direction by the spring 176 and the feed dog 164 again starts a forward movement. Upon deenergization of the fifth solenoid 178, the pulses generated in the secondary winding PT₁₂ of the first pulse transformer PT₁₁ conduct the thyristor 199 to actuate the relay 196 and change over the switching contact element 196c₁. As the result, the relay 196 is kept in a self-holding position, and power supply to the control line 201 is topped. The relay 213 is brought back to its original position to open its normally open contact element 213a₁, which has been closed up to this point, bringing the control line 216 into an unconducted state, thus preventing the unnecessary restart of the timer devices 202 and 215. Upon the return of the relay 213, the variable resistor 221 is selectively actuated by the switching contact element 213c₁, bringing about a condition preparatory for the end non-ravel seaming. Under such condition normal sewing is continued.

(III) End non-ravel seaming operation (Refer to time T_5 in FIG. 13)

When the operation of the foot treadle 134 is changed from the downward direction to the upward direction beyond the rest position as soon as the desired amount of normal sewing has been carried out, then the thread cutting switch S_3 is closed. Accordingly, the relay 233 is energized by the current passing through the needle upper position detecting contact element S_5 while the needle 24 is being lifted. The normally open contact element $233a_1$ of said relay 233 is closed to leave said relay 233 independent of the operation of the thread cutting switch S_3 . Thus the relay 233 is brought into a selfholding position through the normally open side of the switching contact element $190c_1$ due to the change-over of the switching contact element $233c_1$. The control line 232 is supplied with voltage to conduct the transistor 234 and actuate the relay 229. When this relay 229 is actuated, its normally open contact element $229a_1$ is closed to energize the fourth solenoid 129a associated with the electromagnetic switch valve 86. The piston rod 85 is pushed forward to cause the auxiliary actuating lever 122 to rotate about the shaft 105 in the direction of the arrow 137, so that the movable shaft 58 is moved in a direction of arrow 138 through the sleeve 57 whereby the clutch disk 60 is kept to be engaged with the flywheel 47. Accordingly, when the operation of the foot treadle 134 is changed from the downward direction to the upward direction, the main actuating lever 100 is brought back to its original position. The start switch S_1 is still kept closed due to the rotation of the auxiliary, thus maintaining the sewing machine in a high speed operating condition. The first pulse (at the time T_5 in FIG. 13) generated in the secondary winding PT_{22} of the second pulse transformer PT_2 after the operation of the foot treadle 134 in the upward direction conducts the thyristors 235 and 248 to actuate the timer devices 238 and 215. Upon conduction of the thyristor 248, the control line 216 is supplied with voltage and in consequence the transistor 226 is conducted to energize the fifth reversion solenoid 178. The piston rod 174 of the fourth fluid pressure cylinder 171 is pushed up and the feed dog 164 is changed to make a backward movement opposite to that which it has performed up to this point, so as to reverse the work feed. Accordingly, the work is conducted backward and quickly subjected to the end non-ravel seaming. When said end non-ravel seaming is continued for the period preset by the time constant defined by the variable resistor 221 and condenser 223, then the transistor 226 is shut off and the fifth solenoid 178 is deenergized (at the time T_6 in FIG. 13) to allow the reversion timer device 215 to complete its timing in the same way as in the start non-ravel stitching. Accordingly, the reversing shaft 169 rotates in the normal direction by the action of the spring 176 to cause the feed dog 164 to move again in the forward direction. Upon lapse of a period defined between T_6 and T_8 , the timing operation of the timer device 238 stops and the transistor 234 is shut off and the relay 229 is brought back to its original position. Thus the end non-ravel seaming is conducted first backward for a period of T_6 to T_8 and then forward for a period of T_8 and T_9 . As indicated at the time T_8 in FIG. 13, the relay 229 and in consequence its normally open contact element $229a_1$ are brought back to the

original position to deenergize the fourth solenoid. Accordingly, the auxiliary actuating lever 122 returns together with the sleeve 57 with the movable shaft 58 to its original position so as to be disposed parallel with the main actuating lever 100. The clutch disc 60 is pressed to the brake wheel 52 which was previously set in a slow no-load operation, thus bringing the sewing machine into a stepped-down condition.

10 (IV) Thread cutting and stopping operation with the needle kept in an upper position (Refer to the time T_7 in FIG. 13)

When the needle lower position detecting contact element S_6 is opened in such stepped-down condition of the sewing machine, the relay 190 regains its original position because its "OFF" period grows longer than that during which discharge from the condenser 192 continues. Accordingly, when the needle is placed on the machine bed, namely, when the needle upper position detecting contact element S_5 is closed, then the relay 230 is energized by the current passing through the normally closed side of the switching contact element $190c_1$ to have its normally open contact element closed and is brought in a state ready to cut thread. When the thread cutting contact element S_4 is closed (at the time T_7 in FIG. 13), the relay 195 is energized to cause the switching contact element $195c_1$ to be changed over to a state indicated by the dotted line. As the result, the second solenoid 38 is energized to cause the upper and lower threads to be caught by each When when the thread cutting contact element S_4 is opened by the rotation of the thread cutting ring 151 (at the time T_9 in FIG. 13), the relay 195 regains its original position. As the result, the third solenoid 39 is energized instead of the second solenoid 38 to cause the thread cutting mechanism 34 to rotate so as to complete the thread cutting operation. On the other hand, when the relay 195 is actuated, its normally closed contact element $195b_1$ is opened, so that the relay 196 which has been kept in a self-holding position up to this point is brought back to its original position. Accordingly, the normally closed side of the switching contact element of said relay 196 which has been opened up to this point is closed, thus presenting a condition preparatory for the non-ravel seaming of the following cycle of sewing. When the needle 24 is brought to a rising position (at the time T_{10} in FIG. 13), the needle upper position detecting contact element S_5 is opened and the relay 230 and in consequence its switching contact element $230c_1$ are brought back to the original position. As the result, the brake coil 140 is excited by the current passing through the normally closed side of said contact element $230c_1$ and the clutch disk 94 is attracted to said coil 140, so that the sewing machine stops operation with the needle kept in a rising position and the relay 233 is brought back to its original position. Accordingly, the first solenoid 34 is energized to cause the work holding member 25 to be lifted. When the treadle is released the thread cutting switch S_3 is opened.

65 (V) Stopping operation with the needle kept in a lower position

This embodiment permits the sewing machine to be stopped during sewing operation with the needle kept

in a lower position, even where the non-ravel seaming switches S_8 and S_9 are closed in advance, and also prevents the machine from performing non-ravel seaming when it again starts sewing from the aforesaid stopped position. When the treadle is released without changing its depression from the downward to the upward direction during high speed sewing (at the time T_3 to T_4 in FIG. 13) described in Item (II), then the sewing machine is brought into a stepped-down state. When, therefore, the needle lower position detecting contact element S_6 is opened with the needle kept in a lower position, the relay 190 and in consequence its switching contact element $190c_2$ are brought back to the original position. Accordingly, the brake coil 140 and the first solenoid 34 are energized by the current flowing through the normally closed side of said contact element $190c_2$, causing the machine to be stopped with the needle kept in a lower position, and the work holding member 25 to be lifted, and permitting the work to be changed in position. Even if the sewing machine again starts sewing from the condition in which it is stopped with the needle kept in a lower position, the relay 196 is already in an operating position (at the time T_3 in FIG. 13), to prevent the timer devices 202 and 215 from being actuated, so that non-ravel seaming can not be performed when sewing is restarted.

(VI) Manual reversing operation and other procedures

When there is thrown a manual switch S_{10} during the aforementioned stop of the sewing machine so as to manually carry out desired non-ravel seaming, then the fifth solenoid 178 is energized to change the feed dog 164 to a backward movement. When, under such condition, the foot treadle is depressed backward to restart the machine, the work feed is reversed to permit non-ravel seaming or similar operation. Particularly in the embodiment, the reversion timer device 215 is provided with two variable resistors 221 and 222 so as to be selectively actuated by the switching contact element $213c_1$. Accordingly, non-ravel seaming can be effected at the start and end of sewing at different time constants. This means that a single timer device permits the start and end non-ravel seaming to be performed with a freely chosen length, rendering the non-ravel stitching device economically advantageous.

It will now be apparent that the foregoing embodiment of the present invention provides a control system for a sewing machine which enables the non-ravel seaming of the start and terminal ends of sewing thread to be carried out quickly and automatically at the start and end of sewing, thereby elevating operating efficiency and rendering the length of non-raveling seams uniform, and further wherein the timer device (indicated by numeral 92 in the embodiment) for setting the time to start the reverse operation of the work feed mechanism for non-ravel seaming is so designed as to be actuated by pulses obtained, for example, by the switching of a thread cutting contact element so that timing begins to proceed only after the sewing machine is reliably started by the depression of the treadle, thus eliminating the possibility as encountered with the prior art that depending on the manner in which the treadle is depressed, only timing advances, though the sewing machine is not fully started with the resultant failure to perform a proper reverse feed. Moreover, the

non-ravel seaming device of the present invention does not require a sewing machine to be operated with any particular care, so that it offers great advantage in elevating sewing efficiency.

What we claim is:

1. A control system for a sewing machine having
    - a frame,
    - a main shaft rotatably supported on the frame,
    - a reciprocable needle supported on the frame and drivingly connected to said main shaft,
    - work feeding means supported on said frame for advancing or reversing the travel of a work fabric according to the rotation of said main shaft, and
    - means supported on said frame for reversing the feeding direction of said work feeding means, said control system comprising:
      1. drive means drivingly connected to and rotating said main shaft;
      2. clutch means provided between said drive means and said main shaft for operatively connecting said drive means with said main shaft;
      3. a foot treadle operable from a rest position in a downward direction and in an upward direction beyond the rest position, said foot treadle operably connected to said clutch means and operable in said downward direction for actuating said clutch means to rotate said main shaft;
      4. auxiliary actuating means operably connected to said clutch means for actuating the same in replacement of said foot treadle;
      5. operating means connected to said auxiliary actuating means for operating the same;
      6. a first control means connected to said feed reversing means for actuating the same for a predetermined period upon operation of said foot treadle in the downward direction; and
      7. a second control means connected to said operating means and said feed reversing means for actuating both of said means for a predetermined period upon operation of said foot treadle in the upward direction after the desired amount of sewing is finished,
- whereby there can be effected desired non-ravel seaming automatically and quickly at the start and end of sewing only by the operation of said treadle.
2. A control system according to claim 1, wherein said first control means includes
    - a control means operatively connected to said feed reversing means for actuating the same after a predetermined period responsive to the operation of said foot treadle in the downward direction and another control means operatively connected to said feed reversing means for actuating the same for a predetermined period responsive to the completion of the predetermined period of the aforesaid control means.
  3. A control system according to the claim 1, wherein said second control means includes
    - a control means operatively connected to said feed reversing means for actuating the same for a predetermined period responsive to the operation of said foot treadle in the upward direction and an another control means operatively connected to said operating means for actuating the same for a predetermined period substantially equal to or

longer than that of said feed reversing means responsive to the operation of said foot treadle in the upward direction.

4. A control system according to claim 1, wherein said drive means, said clutch means, said auxiliary actuating means and said operating means constitute a clutch and brake motor assembly for rotating said main shaft, said assembly including:

- a. a motor having a bracket,
- b. a flywheel continuously rotated by said motor,
- c. a brake wheel supported on said bracket,
- d. a clutch disk operably connected to said main shaft and selectively movable between a first and a second position to be engaged in the first position with said flywheel for transmitting power to said main shaft or in the second position with said brake wheel for stopping the rotation of said main shaft,
- e. a main actuating lever movably supported on said bracket and operably connected with said clutch disk and said foot treadle for moving said clutch disk between said first and second positions,
- f. an auxiliary actuating lever movably supported on said bracket for moving said clutch disk in replacement of said main actuating lever,
- g. a fluid pressure cylinder provided between said main and said auxiliary actuating levers for operating said auxiliary actuating lever responsive to the operation of said foot treadle in the upward direction.

5. A control system according to claim 4, wherein said main and auxiliary actuating levers are so designed that said main actuating lever moves said clutch disk through said auxiliary actuating lever when said foot treadle is operated in the downward direction, and said auxiliary actuating lever moves said clutch disk independently by the operation of said fluid pressure cylinder when said foot treadle is operated in the upward direction.

6. A control system according to claim 4, wherein the main and the auxiliary actuating levers are so designed that the main actuating lever moves the clutch panel independently when the foot treadle is operated in the downward direction, and the auxiliary actuating lever actuates the clutch panel also independently by the operation of the fluid pressure cylinder when the foot treadle is operated in the upward direction.

7. A control system for a sewing machine having
- a. a frame;
  - b. a main shaft rotatably supported on said frame,
  - c. a reciprocable needle supported on said frame and drivingly connected to said main shaft,
  - d. work feeding means supported on said frame for advancing or reversing the travel of a work fabric according to the rotation of said main shaft,
  - e. means supported on said frame for reversing the feeding direction of said work feeding means,
  - f. thread cutting means movably supported on said frame, and
  - g. means supported on said frame for moving said thread cutting means, said control system comprising:

1. drive means drivingly connected to said main shaft for rotating the same,

2. clutch means provided between said drive means and said main shaft for operatively connecting said drive means with said main shaft,

3. a foot treadle operable from a rest position in a downward direction and in an upward direction beyond the rest position, said foot treadle operably connected to said clutch means and operable in said downward direction for actuating said clutch means to rotate said main shaft,
4. auxiliary actuating means operably connected to said clutch means for actuating the same in replacement of said foot treadle,
5. operating means connected to said auxiliary actuating means for operating the same,
6. a needle positioning means provided between said drive means and said main shaft for stopping said needle in a predetermined position, and
7. a circuit network interconnecting said feed reversing means, said operating means, said moving means for said thread cutting means and said needle positioning means, said network including

- a. a first control circuit operatively connected to said feed reversing means for actuating the same for a predetermined period upon operation of said foot treadle in the downward direction,
- b. a second control circuit for actuating said operating means and said feed reversing means for a predetermined period upon the operation of said foot treadle in the upward direction after the desired amount of sewing is finished, and
- c. a third control circuit for actuating said needle positioning means and said moving means for said thread cutting means responsive to the termination of the operation of said operating means and said feed reversing means, whereby there can be effected desired non-ravel seaming automatically and quickly at the start and end of sewing, said needle being stopped in a predetermined upper position by said needle positioning means, and said needle thread being cut by said thread cutting means, only by the operation of said foot treadle.

8. A control system according to claim 7, wherein said needle positioning means being adapted to arrest said needle in a lower position upon return of said foot treadle to its rest position from the downward direction after the desired amount of sewing is finished.

9. A control system for a sewing machine having
- a. a frame,
  - b. a main shaft rotatably supported on said frame,
  - c. a reciprocable needle supported on said frame and drivingly connected to said main shaft,
  - d. work feeding means supported on said frame for advancing or reversing the travel of a work fabric according to the rotation of said main shaft, and
  - e. means supported on said frame for reversing the feeding direction of said work feeding means, said control system comprising:
1. drive means drivingly connected to said main shaft for rotating the same,
  2. clutch means provided between said drive means and said main shaft for operatively connecting said drive means with said main shaft,

3. a foot treadle operable from a rest position in a downward direction and in an upward direction beyond the rest position, said foot treadle operably connected to said clutch means and operable in said downward direction for actuating said clutch means to rotate said main shaft, 5
4. auxiliary actuating means operably connected to said clutch means for actuating the same in replacement of said foot treadle,
5. operating means connected to said auxiliary actuating means for operating the same, and 10
6. a circuit network interconnecting said feed reversing means and said operating means for actuating the same in response to the operation of said foot treadle, said network including
- a. a first control circuit operatively connected to said feed reversing means for actuating the same after a predetermined period responsive to the operation of said foot treadle in the downward movement, 15
- b. a second control circuit operatively connected to said feed reversing means for actuating the same for a predetermined period responsive to the completion of the predetermined period of said first control circuit, 20

- c. a third control circuit connected to said feed reversing means for actuating the same for a predetermined period responsive to the operation of said foot treadle in the upward direction after the desired amount of sewing is finished, and
- d. a fourth control circuit connected to said operating means for actuating the same for a period substantially equal to or longer than that of said feed reversing means responsive to the operation of said foot treadle in the upward direction, whereby there can be performed desired non-ravel seaming automatically and quickly at the start and end of sewing only by the operation of said foot treadle.

10. A control system according to the claim 9, wherein said second and third control circuits are formed into a single timer circuit capable of setting two different periods for non-ravel seaming.

11. A control system according to claim 9, wherein said circuit network is provided with a switching means to energize at least one of said four circuits responsive to the rotation of said main shaft by the operation of said foot treadle.
